UNITED STATES PATENT OFFICE

CLARENCE RINGWALD, OF NORTH HAMPTON, OHIO

DESIGN FOR AN AGITATOR

Application filed July 30, 1932. Serial No. 44,497. Term of patent 7 years.

To all whom it may concern:

Be it known that I, CLARENCE RINGWALD, a citizen of the United States, residing at North Hampton, in the county of Clark and State of Ohio, have invented a new, original, and ornamental Design for Agitator, of which the following is a specification, reference being had to the accompanying drawing, forming part thereof.

In the accompanying drawing:

The figure is a perspective view of an agitator showing my new design,

I claim:

The ornamental design for an agitator as shown.

CLARENCE RINGWALD,
